ATTACHMENT FOR WINDSHIELDS

Emil Fluger, New York, N. Y.

Application July 31, 1941, Serial No. 404,802

8 Claims. (Cl. 40—16)

This invention relates to attachments for the frames of automobile windshields, and one object is to provide such an attachment with means for securing the same in place and with means for mounting or otherwise securing to the attachment any cards, placards, photographs, or legend-bearing devices.

One purpose for which the attachment may be applied, consists in mounting a legend such as "Drive carefully" in the lower or horizontal member of the attachment, and mounting photographs of members of the driver's family in the upright member thereof. By virtue of the position of these signs, as they might be termed, being at all times before, and readily visible to the driver, his attention will be repeatedly, if not constantly, arrested thereby, and they should have the effect of checking any tendency to careless or reckless driving. It is believed that such reminders will tend to prevent many accidents by exercising a restraining effect upon the driver always to act cautiously so as to prevent a possible accident.

The attachments might obviously be put to uses other than that above-outlined, and it is therefore not desired nor intended to limit the application of the invention to any particular use to the exclusion of other possible uses.

The above and other objects will become apparent in the description below, wherein characters of reference refer to like-numbered parts in the accompanying drawings, forming a part hereof. The drawings are intended to serve the purpose of illustration only, and it is not intended nor desired to limit the invention in any manner to the specific details of construction shown excepting as may be required within the scope of the invention and of the appended claims.

Referring briefly to the drawings, Figure 1 is a fragmentary elevational view of one type of an automobile windshield and adjacent parts, as seen from a position in the front seat of the vehicle, showing one form of the attachment applied thereto.

Figure 2 is similar view of another type of windshield, showing a modified form of attachment applied thereto.

Figure 3 is a similar view showing still another modified form of the attachment applied to a windshield of the type shown in Figure 2.

Figure 4 is a similar view showing yet another modified form of the attachment applied to a windshield of the type shown in Figure 2.

Figure 5 is a cross-sectional view taken on the line 5—5 of Figure 1.

Figure 6 is a cross-sectional view taken on the line 6—6 of Figure 2.

Figure 7 is a cross-sectional view taken on the line 7—7 of Figure 5.

Figure 8 is a cross-sectional view taken on the line 8—8 of Figure 6.

Figure 9 is a cross-sectional view taken on the line 9—9 of Figure 4.

Figure 10 is a cross-sectional view taken on the line 10—10 of Figure 2.

Referring in detail to the drawings, the numeral 11 indicates a windshield of the divided or peaked type, having the frame or moulding 12 along the base thereof, the mouldings 13 along the sides thereof, and the moulding 14 along the top thereof. The center bar or moulding 15 of the windshield frame, which divides the windshield into two equal halves at an angle to each other, rises between the mouldings 12 and 14.

20 The attachment applicable to this form of windshield frame comprises a center or upright member 16 securable to the bar 15 in any desired manner, as, for instance, by means of spring clips 17 which embrace the bar; and a pair of lateral or base members 18 and 19 extending from the lower end of the member 16 and also attachable to the moulding 12 by similar clips 17.

The lower end of the member 16 is bendably attached to a plate or the like 20, by means of a hinge 21, and the lateral members 18 and 19 are likewise attached to the sides of the plate 20 by means of hinges 22. Each of the members 16, 18, and 19 comprises a body 23 bellied as shown to conform to the contour of the moulding to which it is attached. The opposed lateral edges 24 of each of these bodies 23 are doubled back to form yieldable guides 24 whereby a placard 25 or cards or photographs 26 may be mounted on the body 23 and yieldably retained therein. The placard or placards may bear a legend, such as "Drive carefully," and the cards or photographs may bear any suitable representations or pictures.

It is to be noted that when this attachment 45 has been mounted against the windshield frame, it does not in any manner obstruct the vision of the driver, yet the visible signs, pictures, or the like mounted therein are at all times before and readily visible to the driver.

50 The members 16, 18, and 19 are hinged to the plate 20 so that the device may be deformed as necessary to accommodate the outline of the particular windshield frame to which it is to be attached. This is desirable because the various manufacturers' models of automobiles differ in

55

their angular measurements for the divided type of windshields.

The windshield shown in Figure 2 is the undivided or straight, flat type, which is more commonly found on older models of automobiles. Herein the lower horizontal section of the windshield frame or moulding is shown at 21, surrounding the glass 28. The attachment comprises a base member 29 which is fixed to the frame section 21 by any suitable means, such as the spring clips 30, similar to the clips 17. An upright member 31 is hinged at 32 to the member 29, and this member is urged back against the surface of the glass by a pair of spring fingers 33 anchored in the member 29 and insertable into holes 34 in opposed sides of the member 31. The lateral edges of the member 31 may be provided with yieldable ears 35 so that cards or photographs may be held against the surface of the member 31. The visible surface of the member 29 may have any suitable legend or legends printed or pasted thereon. (In Figure 10 the spring finger 33 is shown bent forcibly to the left, simply for the sake of clarity.)

The form of attachment shown in Figure 3 is somewhat similar to that of Figure 2, in that the visible surface of the lower or base portion is adapted to have legends pasted or printed thereon; otherwise it is of the type suitable for divided windshields. It comprises the upright member 36, provided with card mounting clips 37, and hinged at its lower end at 38 to the plate 39. The base members 40 and 41 are hinged at 42 and 43, respectively, to the plate 39, and are secured to the lower members 44 of the windshield frame by means of the clips 45. The upright member 36 is similarly secured by clips 45 against the dividing bar 46 of the windshield frame. This form is, obviously, also adjustable to the particular angularity of the divided windshield frame to which it may be attached.

The form of attachment shown in Figure 4 is somewhat similar to that shown in Figure 1 excepting that it is intended for the straight, flat type of undivided windshield. It comprises the lower or base member 47 which is attached, as by the clips 48, to the lower section 48a of the windshield frame. Excepting for a small area in the center of the member 47, its opposed edges 49 are doubled back, in the same manner as above-described, to provide yieldable retaining means for placards or cards mounted on the member, the visible surface 50 of which is bellied in the same manner as the surface 23 above-described, in order to fit the contour of the frame 48a. The upright member 51 is similarly formed, having the bellied surface 50 and the double-back ears 49. The member 51 is hinged at 52 to the member 47, and an inverted U-shaped spring 53, whose ends are anchored in the member 47, normally urges the member 51 against the glass 54.

It is apparent from the above that an attachment has been provided for windshield frames, whereby legends, placards, pictures, or notices of all kinds may be conveniently mounted before the driver where they will be visible to him at all times without in any manner interfering with his clear vision of the road. Means has also been provided for making the attachment applicable to any common or standard type of windshield frame. And since provision has also been made for yieldably mounting any article of the type mentioned in the attachment, it is apparent that such articles may be readily removed or replaced.

by others. Likewise, the attachment itself may be readily removed, if and when desired.

Obviously, modifications in form and structure may be made, without departing from the spirit and scope of the invention.

I claim:

1. In combination with the base sections of the frame of a divided windshield having a central upright bar dividing the windshield into two equal sections, a pair of mutually joined members attached to said base sections, an upright member pivoted to and extending from said members at the junction of said members, means for attaching said members to said sections, and means for attaching said upright member to said bar, said members having means for mounting cards or the like thereon.

2. In combination with the base sections of the frame of a divided windshield having a central upright bar dividing the windshield into two equal sections, an upright member having means for attaching the same to said bar, a plate hinged to the lower end of said member, a pair of members attached to said base sections and hingedly attached to said plate, and means for attaching said pair of members to said sections, said members having means for mounting cards or the like thereon.

3. In combination with the base sections of the frame of a divided windshield having a central upright bar dividing the windshield into two equal sections, an upright member having means for attaching the same to said bar, a plate hinged to the lower end of said member, a pair of members attached to said base sections and hingedly attached to said plate, and means for attaching said pair of members to said sections, said members having the bodies thereof bellied, said members having means for mounting cards or the like thereon.

4. In combination with the base sections of the frame of a divided windshield having a central upright bar dividing the windshield into two equal sections, an upright member having means for attaching the same to said bar, a plate hinged to the lower end of said member, a pair of members attached to said base sections and hingedly attached to said plate, means for attaching said pair of members to said sections, and means for mounting cards or the like on said members.

5. In combination with the base sections of the frame of a divided windshield having a central upright bar dividing the windshield into two equal sections, an upright member having means for attaching the same to said bar, a plate hinged to the lower end of said member, a pair of members attached to said base sections and hingedly attached to said plate, and means for attaching said pair of members to said sections, said attaching means comprising spring clips on said pair of members adapted to embrace said sections, said members having means for mounting cards or the like thereon.

6. In combination with the base sections of the frame of a divided windshield having a central upright bar dividing the windshield into two equal sections, a pair of mutually joined members attached to said sections, an upright member extending from said members at the junction of said members, means for attaching said members to said base sections, and means for attaching said upright member to said bar, said members having means for mounting cards or the like thereon.

7. In combination with the base sections of the

frame of a divided windshield having a central substantially upright bar dividing the windshield into two equal sections, a substantially upright member having means for attaching the same to said bar, a pair of members pivotally secured to the lower end of said upright member and adapted to be mounted against said base sections, said members having means for mounting cards or the like thereon.

8. The device set forth in claim 7 wherein said means for attaching said upright member to said bar comprises a pair of opposed complementary spring fingers adapted to releasably clamp against the sides of said bar, said members having means for mounting cards or the like thereon.

EMIL FLUGER.
